REFRIGERATING APPARATUS

Norman M. Thomas, Brooklyn, N. Y.

Application January 17, 1934, Serial No. 706,951

7 Claims. (CL 62—108.5)

This invention relates to mechanical refrigerating apparatus and particularly to the construction of a freezing or ice making tray for use in the cooling unit of such an apparatus.

5 It is an object of the invention to provide a tray from which a small number of ice cubes may be removed without disturbing the other cubes in the tray.

10 A further object of the invention is to provide a freezing tray from which any or all of the cubes may be removed without unduly thawing them, so that practically all of the frozen substance of each cube is available for cooling purposes.

15 Other objects and advantages of the present invention will be apparent from the following description and accompanying drawing wherein:

Figure 1 is a perspective view, partly broken away, showing a freezing tray embodying one form of the invention.

20 Figure 2 is a front elevational view of the tray showing one of the sections thereof in a position in which tap water can be run over that section alone.

25 Figure 3 is a sectional view taken on the line 3—3 of Figure 2, showing details of one form of grid construction which may be used in my improved tray.

Referring to the drawing, 10 indicates generally a freezing tray consisting of three hinged sections 11, 12, and 13 respectively. Each of these sections is relatively long and narrow, and in employing my invention any number of sections as desired may be used. However, for the purpose of illustration three such sections are shown, each section being hinged to the other as indicated at 14 to provide the complete tray. 30 A looped strap 16 is provided on the front vertical wall of each section and each strap has an opening 17 extending longitudinally thereof and horizontally with respect to the operating 35 position of the tray. A pin 18 extends through each of the loops 16 when the tray is filled with water and placed in a refrigerator, whereby to prevent relative motion between the respective 40 sections.

45 The removable grid member 19, one of which is provided for each section of the tray, comprises in the present instance a single corrugated spring metal strip, and is so constructed and arranged that each corrugation 20 is substantially V-shaped throughout its width. Each end of the grid terminates in a relatively horizontal flange 21 which projects over and beyond the front and rear vertical walls of each section. The construction of the grid member is such that when

5 pressure is applied to each of the horizontally extending flanges 21 the grid member 19 will be flexed upwardly and thereby each of the triangular shaped blocks of ice formed in the V-shaped depressions of the grid will be loosened.

In the operation of my device the tray is assembled as shown in Figure 1 with the pin 18 extending through each of the loops 16 so as to maintain the three sections 11, 12 and 13 in a line. When the water in the tray has been frozen 10 and only a relatively small number of cubes is desired for immediate use the tray is removed from the freezing compartment of the refrigerator and the pin 18 is removed from the loop 16 provided on the section 13 as indicated in 15 Figure 2. The section 13 because of its hinged connection with the adjacent section 12 may then be turned about its hinge as indicated in Figure 2. This section 13 is then held under running water 20 in order to loosen the ice formed therein from the side walls of the section. The section may 25 then be returned to the dotted line position indicated in this figure and the grid member 19 flexed as previously described so as to loosen each block of ice from the grid.

30 By the construction just described it is apparent that it is necessary to run water over only one section of the tray at a time as distinguished from previous structures wherein in order to remove one or more cubes it has been necessary to run water over the whole tray thereby loosening all the cubes or blocks of ice contained therein. It will also be obvious from the foregoing description that the cubes or blocks in any section may 35 be removed independently of the cubes in any other section.

While I have shown and described this specific embodiment of my invention it will be apparent that other forms may be adopted all coming within the scope of the appended claims.

40 I claim:

1. A freezing receptacle for mechanical refrigerators comprising a tray, formed of a plurality of sections hinged to each other longitudinally of the tray and means for maintaining the sections in a line during the freezing operation, said means comprising a loop member attached to each section of the tray and a pin 45 removably inserted through said loops.

2. A rigid freezing tray for mechanical refrigerators, said tray being formed of a plurality of water containing sections pivotally connected to one another, and means for rigidly connecting the sections with one another to form the rigid tray.

3. A freezing tray for mechanical refrigerators,

said tray being formed of a plurality of water containing sections hingedly connected to one another, a latch element on each of said sections, and a latch element cooperating with the latch elements of the sections for connecting said sections in rigid relationship.

4. A freezing tray for mechanical refrigerators, said tray being formed of a plurality of long and narrow water containing tray sections with the 10 long sides thereof disposed in side by side relation, means for hingedly connecting the sections, said means extending longitudinally of the sections, latching means at the narrow ends of the sections, and latching means cooperating with 15 the first latching means for connecting the sections in rigid relationship.

5. A freezing tray for mechanical refrigerators, said tray being formed of a plurality of water

containing sections pivotally connected to each other at the upper parts thereof, and means connecting the sections to maintain them in a line during the freezing operation.

6. A rigid freezing tray for mechanical refrigerators, said tray being formed of a plurality of rigid water containing sections hingedly connected to one another, and means for rigidly connecting the sections with one another to form 10 the rigid tray.

7. A freezing tray for mechanical refrigerators, said tray being formed of a plurality of rigid water containing sections hingedly connected to one another, and means for rigidly connecting 15 the sections with one another to form the rigid tray.

NORMAN M. THOMAS.
